UNITED STATES PATENT OFFICE.

JOHN F. ISBELL, OF LOS ANGELES, CALIFORNIA, ASSIGNOR, BY MESNE ASSIGNMENTS,
TO GEORGE L. KNIGHT, OF LOS ANGELES, CALIFORNIA.

CONCENTRATOR.

Specification of Letters Patent. Patented May 29, 1917.

1,227,792.

Application filed December 17, 1912. Serial No. 737,813.

To all whom it may concern:

Be it known that I, JOHN F. ISBELL, a citizen of the United States, residing at Los Angeles, in the county of Los Angeles and State of California, have invented a new and useful Concentrator, of which the following is a specification.

This invention relates to a concentrator and slime separator, and is an improvement over my application, filed April 6, 1912, Serial No. 688,855, the machine constituting this invention being adapted for use both in concentration and in slime separation.

The main object of the present invention is to provide improved means for first stratifying the contents of the ore according to density and then immediately separating the heavier lower portions of the stratified material from the remainder of the ore.

A further object of the invention is to provide for directing against the advancing body of stratified material, a current of water moving directly in opposition to the movement of the heavier portions of the ore, and serving to clean or wash away from such heavier portions, the lighter portions of the ore.

A further object of the invention is to provide for convenient and accurate regulation of the operation of the separating means.

Other objects of the invention will appear hereinafter.

The accompanying drawings illustrate an embodiment of the invention, and referring thereto:

Fig. 1 is a plan of the machine.

Fig. 2 is a side elevation thereof.

Fig. 3 is a plan of a portion of the lower end portion of the concentrator table.

Fig. 4 is a section on line x^4-x^4 in Fig. 3.

Fig. 5 is a vertical section on line x^5 in

Fig. 1.

Fig. 6 is a section on line x^6-x^6 in Fig. 3.

Fig. 7 is a perspective of one of the separators.

Fig. 8 is a side elevation of the head motion for the table.

The concentrator and slime separator constituting the present invention, comprises a table 1, supported by suitable supports 2 on a base 3, so as to be capable of longitudinal movement, said table being provided with riffles and with separator means as hereinafter set forth, and a head motion

4 connected to said table to produce a reciprocating longitudinal movement thereof.

The table 1 may be of any suitable form, for example, rectangular, having side walls 6 and having an end wall 7 at the upper or head end of the table, the lower end of the table being open and terminating in a downturned lip or tail plate 8 over which

the tailings and middlings are discharged.

The table is preferably mounted so as to have a slight downward inclination from the head to the tail end, and is provided with a slight rise 8', see Fig. 4, at the tail end so as to dam up or hold back the ore and water at that point. Any suitable feed

or supply means is provided at the head end of the table, consisting, for example, of feed boxes 10 adapted to receive the ore and feed water and to discharge the same over a lip 10' at the upper end of the feed

box, the ore and water then passing under the feed box on to the surface of the table 1.

The table 1 and the walls 6 and 7 may be made of wood or any other suitable material and said table may be covered with a suitable waterproof surface such as linoleum, indicated at 12 (Fig. 4). The table is shown as provided with a central partition or wall 13 extending longitudinally

thereof and dividing the table into two similar table portions or units, each provided with its own feed box 10 and with similar separating and discharge devices so

that a description of one-half of the table will serve for both. Each half of the table is provided with riffle means tending to produce concentration along a central longitudinal line on said half table, but it will be understood that the concentration may be effected upon any longitudinal line on the table.

On the surface of each half of the table 1 are provided riffles 15 and 15' extending along the table surface from the side thereof, obliquely toward the tail end of the table and terminating adjacent to the longitudinal concentrating line. Thus

in the form shown herein, where the concentrating line is at the center of the half portion of the table, these riffles will terminate adjacent to the central longitudinal line of said half portion. The riffles 15

which are nearer the head end of the table are preferably separated at their tail ends to provide passages 16 through which the ore and water may pass, and the riffles 15

2
nearer the tail end of the table are joined at their inner ends to separating devices or cut outs, the function of these lower riffles being to conduct the stratified material to these separating devices.

Each separating device consists of a box 18, preferably of metal, the lower portion of said box being V-shaped in horizontal section, the divergent walls 17 of the lower portion of said box resting on the table surface and abutting at their outer ends against the lower ends of the riffles 15' so that said walls 17 are in line with the respective riffles and form, substantially, continuations of the riffles. A top plate 19 extends above and is connected to the walls 17 and is provided with diverging arms 20 having extensions 20' adapted to extend over the tail ends of riffles 15'. The riffles 15' are provided with flanges extending horizontally along their upper edges and projecting toward the center line or axis of the table into the adjacent riffle spaces, said flanges being, for example, formed by metal strips 21 somewhat wider than the body of the riffle and secured to the riffle by screws or brads. The bodies of the riffles 15 and 15' may consist of wooden strips. At their forward ends these separator strips 21 abut against the outer ends of the arms 20 of the top plate aforesaid, said arms 20 being at their outer ends, somewhat wider than the riffles 15' and increasing in width toward their inner ends. The arms 20 and top plate 19 incline upwardly in a forward direction, so that the space below the top plate increases in height forwardly. The side walls 17 of the separator box converge forwardly and terminate in a wedge shaped forward end portion 18' of the box, and a bottom plate or flange 24 extends from said end of the box forwardly between the side walls 17, said plate or flange 24 having a horizontal lower face resting on the table surface and having an inclined upper face 24' so that the said plate tapers to a knife edge at its forward end. An outlet pipe or tube 25 extends through said bottom plate, said pipe preferably screwing into said plate so as to be adjustable therein by turning the pipe, the said pipe extending downwardly through the table 1, for conveying the concentrates to any suitable delivery means. The separator box is further provided with a water supply means adapted to deliver water into the space or chamber 26, within the box, so that said water will pass rearwardly beneath the top plate 19 of the box. To distribute the water uniformly and without violent agitation, the water is preferably supplied over said top plate 19, the said box having an upper portion 28 constituting a water box extending over said top plate and closed at the top by a top plate 29, leaving a space between the top plates 19 and 29 with which

communicates a water supply pipe or nipple 30 connected through a valve 31 with a water supply pipe 32. A pipe or hose 33 leading to any suitable source of water supply is connected through a valve 34 to the pipe 32, 70 said pipe 32 extending longitudinally over the series of separator boxes 18, so as to supply water to all of the boxes for one table unit. An opening 35 is provided in the top of the separator box above the bottom plate 24 and outlet pipe 25 to enable access to and inspection of said space, and a closure plate 37 is provided for this opening which is movably secured in position by a thumb screw 38. The lower top plate 19 preferably terminates about on a line with the forward edge of the bottom plate 24, so that the water delivered from the space above said top plate passes into the space above said bottom plate and then rearwardly under 85 the plate 19. The upper portion 28 of the separator box extends above the riffles 15' and is V-shaped or tapered rearwardly so as to present a sharp edge in the path of the stream of water and material passing over 90 the top plate 19 of the separator, the side walls of this upper portion of the separator box being continued forwardly and converging forwardly to form a sharp edge so that the upper portion of the separator box is 95 diamond shaped. This construction of the upper portion of the separator box provides for minimum obstruction to the stream of water and material flowing past the separator box. Parting strips 39 are provided at 100 opposite sides of the separators and spaced therefrom to leave passages at each side of the upper portions of the separators, said strips being secured to the tops of the riffles and of the separators by screws 39' which 105 also secure said strips to cross pieces 36, serving as braces. The lower edges of the side strips 39 are flush with and rest upon the riffles 15' and the lower portions of said strips are notched as shown at 53, see Fig. 110 5, to receive the boxes 18. After the last set of riffles 15', leading to the separators, there may be additional riffles 15 for giving a final wash of the tailings on the separator riffles 15', the inner ones of said terminal riffles 15 115 discharging at their inner and lower ends into a central discharge channel 54, below and between the side strips 39 so that the heavier portions of such tailings are brought to the center along with the tailings from 120 the separator boxes, and means are provided for separately collecting the combined discharge from this central portion, so that the same may be used as middlings and worked over again if desired. For this purpose, deflectors or wings 55 are pivotally mounted at 125 56 on the tail plate or lip 8 of the table and any suitable conveying means such as a chute 57 is located beneath said lip adjacent to said deflectors so that the material will be 130

guided by said deflectors onto said conveying means. The parting strips 39 are connected at their upper or head ends by plates 58 extending inwardly and rearwardly to 5 form a V-shaped deflector which parts the upper portions of the forwardly moving material and deflects it to either side of the space or passage 59 between the parting strips.

10 The head motion 4 may be of any suitable type, but is preferably of the type shown in Fig. 8, as I have found that this construction of head motion gives the most rapid travel to the material on the table. Said 15 head motion comprises a frame 40, a shaft 41 journaled in said frame and driven by pulleys 42, an eccentric 43 carried by said shaft, a lever 44 operated by said eccentric, a rocker arm 45 pivotally mounted at 45' on 20 frame 40, a link 46 pivotally connected to said lever 44 and forming in conjunction therewith, a toggle, an adjustable mounting 47 for said toggle link 46, said adjustable mounting being mounted to slide vertically 25 on the frame 40 and adjusted by a screw 48. The rocker arm 45 is connected to a bar 49 engaging, by nuts 50 thereon, with a bracket 51 on the table 1, a spring 52 being interposed between frame 40 and a collar 53 on 30 the bar 50. A ring 60 is rotatable on eccentric 43 and bears against lever 44, said eccentric turning within said ring, and as the eccentric turns, the point of contact of ring 60 with lever 44 shifts along the curved face 35 44', the ring rolling along said face, so that by suitably curving this face, the motion of the lever and of the toggle may be caused to give a sharper return action than is possible with direct crank action on the toggle. This 40 head motion operates in the usual manner to produce a longitudinal reciprocation of the table with a rapid return or jerk at the forward end of its stroke, tending to cause the solid material on the table to become dis- 45 placed longitudinally of the table by back travel of the table under such material, so that there is a continual tendency due to such motion, for the heavy material to travel longitudinally of the table from the head to- 50 ward the tail end thereof.

The supports 2 for the table may consist of elastic metal bars connected to the base 3 and to the table 1, so as to permit of reciprocating movement of the table.

55 The operation is as follows: Ore, together with feed water is supplied to the feed box 10, and passing onto the upper end of the table is distributed uniformly over the width of the table, and carried longitudinally of 60 the table by the combined action of the current of water flowing from the upper toward the lower end of the table, and the displacing action due to the longitudinal reciprocation by the head motion as above described.

65 This longitudinal reciprocation also pro- duces a settling action tending to cause the heavier material to settle or stratify toward the bottom. The amount of material supplied is sufficient to cover the riffles on the table and extend somewhat above the riffles, 70 the dam or rise 8' at the tail end of the table serving to retain the table at the proper depth. That portion of the material which is above the riffles is carried over the riffles by the action of the current, whereas that 75 portion of the material which is below the top of the riffles is carried obliquely inward toward the concentrating line or longitudinal axis of the machine, and the preliminary riffles 15 operate in this manner to separate 80 from the body of ore the heavier constituents and deliver them through the central passages 16 to the first separator 18. The riffles 15' leading to the side walls of the respective separators operate in similar manner to convey to the respective separators the heavier materials which have settled below the top of the respective riffles 15', while allowing the lighter materials above the top of the riffles to be washed over the riffles by 90 the flow of said water. This skimming or separating action of the riffles 15 and 15' is made more effective by the flanges or strips 21 on top of said riffles, said flanges extending into the riffle space on the head side of 95 the riffles, and sharply dividing the material below said flanges from the material above the same, so as to give a sharper definition to the separating action. By the above described means the concentrates or values of 100 the ore are first stratified and caused to settle below the top or separating edges of the riffles, and are then deflected by the riffles so as to be forced into the respective separators, while the lighter constituents or gangue is carried over the riffles by the water flowing longitudinally of the table over the riffles. Necessarily, however, the separating action of any one riffle is not perfect, as there will be more or less gangue or sand mixed with 105 the concentrates collected by each riffle and on the other hand, for the preliminary riffles at least, more or less of the values will pass over the riffles on account of not having had sufficient opportunity to settle below the tops of the riffles. By providing a large number of riffles acting successively on the ore, it is possible to insure that substantially all of the values will eventually pass 110 below the tops of the riffles, and will be delivered to the separators, and the gangue or lighter material which is washed over the terminal riffles and carried over the tail end of the table is, therefore, substantially free of values. To clean the concentrates collected 115 by the riffles and carried to each separator box, without having to subject it to a further riffling operation, means are provided for washing such concentrates by the action of a current of water flowing back in oppo- 120

125

130

sition to the movement of the concentrates toward the discharge or outlet therefor, this means consisting of the water supply means aforesaid for the separator boxes, the water from said water supply means passing into the water box or space above the plate 29 and then down into the space 26 and then backwardly under the plate 29 in opposition to the forward movement of the ore under said plate 29. The concentrates collected by the riffles 15 move forwardly under the plate 19 within the separator box by the displacing action due to the longitudinal reciprocating motion of the table and by reason of the forward 15 inclination or rise of the bottom plate 24 and of the accumulation of ore on said plate due to elevation of the discharge pipe 25 above said plate 24, the body of the concentrates has to rise when passing forwardly to the said outlet so that its forward motion is retarded and sufficient opportunity is thereby given for the wash water in passing backwardly over the ore to clean the ore and carry the lighter materials out of the separator box and above the body of ore into the separator box. This material so separated from the concentrates will, in general, be in the nature of middlings and it is desirable to keep the same separated from the lighter 20 material or gangue which passes over the riffles 15 and 15', this function being effected by the side strips 39 extending parallel to the concentrating line, and spaced sufficiently from the sides of the water boxes 28 to enable the material thus washed from the concentrates to pass longitudinally of the stream in a separate stream from the main body of ore, this separate stream being delivered at the tail end of the machine between the deflectors or wings 55 and being guided thereby to any suitable collecting chute, such as indicated at 57, the passage 64 between the side strips constituting a clear water channel which is separated from the 35 current over the main body of the riffles by said parting strips, whereby the clear water from the backwash is kept separate from the feed water. Moreover, said parting strips serve to shear off or hold back the upper, lighter strata of material and keep it from passing into the central passage 54, and into the cut outs or separator boxes. By spreading the wings 55 more or less, they may be made to take in the tailings from the 40 innermost riffle space in addition to the middlings coming from between the side strips 39 and from the inner riffle spaces directly into the central channel 54.

On account of the protection of the heavier material after it settles into the spaces between the riffles, and of the immediate separation of such material and its collection and discharge through the separators, it is possible with this machine to concentrate 65 materials containing large proportions of

slimes, the heavier portions of the slimes passing with the concentrates notwithstanding their fine state of division. By adjusting the outlet pipes 25 to different heights, the character of the concentrates discharged through the several pipes may be regulated as desired, it being understood that the more the pipe is elevated the higher the concentrates have to bank up before they can pass into the pipe and the concentrates thereby separated will be cleaner but will be smaller in quantity.

What I claim is:

1. In a concentrator, a table, means for longitudinally reciprocating said table, means for supplying water and material at one end of said table, riffles extending obliquely on said table from one side thereof to a concentrating line extending longitudinally of the table, and separators having walls continuous with the riffles and having outlet means through which the material is guided by said riffles and walls, said outlet means being vertically adjustable to control the height of the discharge therethrough. 90

2. In a concentrator, a table, means for longitudinally reciprocating said table, means for supplying water and material at one end of said table, riffles extending obliquely on said table from one side thereof to a concentrating line extending longitudinally of the table, and separators having walls continuous with the riffles, said riffles having flanges extending from the tops of the riffles inwardly over the space between the riffles, and said separators having top portions extending between the separator walls and having portions abutting the inner ends of the flanges on said riffles. 95

3. In a concentrator, a table, means for longitudinally reciprocating said table, means for supplying water and material at one end of said table, riffles extending obliquely on said table from one side thereof to a concentrating line extending longitudinally of the table, and separator boxes having walls continuous with the riffles, a top plate for each separator box, each separator box being provided with a water chamber above said top plate having an outlet into the separator chamber at the rear of said top plate, and parting strips at opposite sides of said water chamber and spaced therefrom to form a central passage between said parting strips. 105

4. In a concentrator, a table, means for longitudinally reciprocating said table, feed means at one end of the table, riffles extending obliquely on said table, separator boxes having side walls continuous with said riffles, and parting strips extending above and at each side of said separator boxes. 115

5. In a concentrator, a table, means for longitudinally reciprocating said table, feed means at one end of the table, riffles 125

extending obliquely on said table, separator boxes having side walls continuous with said riffles, means for supplying wash water to the separator boxes, said boxes being open 5 at the rear for receiving ore and for discharge of wash water, outlet means in each separator box, and parting strips extending above and at each side of said separator boxes, forming a clear water channel adjacent to the separator boxes.

6. An ore separator, comprising a horizontal shaking table, an ore outlet leading through the table and a cutoff extending across the table, said cutoff comprising 15 means forming a chamber leading to the ore outlet, means forming a second chamber above the first chamber, there being a water inlet for the second chamber so that as the gangue approaches the ore outlet it will 20 be met by a stream of clear water which will carry the lighter material upwardly and past the ore outlet.

7. In combination, a longitudinally reciprocating separator table, a horizontal 25 strata separator member extending above the table, a chamber formed above the table and communicating with the space beneath said separator member, an outlet means communicating with said chamber, and means 30 for supplying water to said chamber at a point in the upper portion of the chamber to produce a stream of water flowing upwardly under the said separator member in opposition to the flow of gangue.

35 8. An ore separator comprising, in combination with a longitudinally reciprocating separator table, an inclined strata separator member extending above the table and spaced therefrom to form an inclined channel between said member and table through 40 which the heavier portion of the ore passes, outlet means in the said table communicating with said channel to receive the ore therefrom, and means for forcing a current 45 of water upwardly in said channel in opposition to the movement of the ore therethrough.

9. In an ore separator, a longitudinally reciprocating separator table, a chamber on 50 said table, provided with a channel at one end for receiving the ore passing along the table, outlet means in the table communicating with said chamber, and means for supplying water to said chamber to produce 55 a current of water through said channel in opposition to the movement of ore therethrough.

10. An ore separator comprising a table, means for longitudinally reciprocating said 60 table to cause the ore to advance thereon and

become stratified, an ore outlet means leading through the table, and a cutoff comprising a separator member spaced above the table to permit the heavier portion of the ore to pass beneath said separator member, 65 said cutoff also comprising walls for guiding the ore passing beneath said separator member to said ore outlet, and water inlet means for supplying water to the space between said walls.

70 11. An ore separator comprising a horizontal shaking table, means forming a concentrates outlet through the table, and a cut-off extending across the table, said cut-off comprising means forming a chamber leading to the concentrates outlet, and means forming a second chamber above the first chamber, there being a water inlet for the second chamber, so that as the ore approaches the concentrates outlet it will be 80 met by a stream of clear water which will carry the lighter material upwardly and past the concentrates outlet.

12. In combination, a longitudinally reciprocating separator table upon which the 85 gangue flows longitudinally, a strata separator member extending above the table, a chamber formed on the table and communicating with the space beneath said separator member, an outlet means communicating with said chamber, and means for 90 supplying water to said chamber to produce a stream of water flowing upwardly under the said separator member longitudinally of the table in opposition to the longitudinal flow of gangue.

95 13. An ore separator comprising a table, means for longitudinally reciprocating said table to cause the ore to advance thereon and become stratified, an ore outlet means leading through the table, and a cut-off comprising a separator member spaced above the table to permit the heavier portion of the ore to pass beneath said separator member, 100 said cut-off also comprising walls for guiding the ore passing beneath said separator member to said ore outlet, and water inlet means for supplying water to the space between said walls and adapted to produce a stream flowing longitudinally of 105 the table in opposition to the longitudinal flow of the gangue.

110 In testimony whereof, I have hereunto set my hand at Los Angeles, California, this 20th day of November, 1912.

JOHN F. ISBELL.
